CLAIM

The ornamental design for a bowl with friction material, as shown and described.

DESCRIPTION

FIG. 1 is a left side elevational view of the bowl with the friction material, showing the new design; the right side elevation view is a mirror image thereof;

FIG. 2 is a rear elevational view thereof;

FIG. 3 is a front elevational view thereof;

FIG. 4 is a bottom plan view thereof;

FIG. 5 is a top plan view thereof; and,

FIG. 6 is a perspective view thereof.
